UNITED STATES PATENT OFFICE

JONATHAN BOY FREEZE, OF MIDDLETOWN, OHIO, ASSIGNOR TO THE AMERICAN ROLLING MILL COMPANY, OF MIDDLETOWN, OHIO, A CORPORATION OF OHIO

MACHINE FOR CORRUGATING SHEET METAL

Application filed March 28, 1928. Serial No. 265,485.

My invention relates to machines for minimum forming corrugations in flat sheet-metal, and particularly to a machine wherein the sheet metal to be corrugated is passed continuously through a series of rolls which will fold successively the crests and valleys of the corrugations. 55

Prior practice generally has applied two methods for corrugating metals. One consists of passing flat sheets through a double-slide toggle-press or a similar machine, and a corrugation is formed with each stroke of the slide. After forming the first corrugation the sheet is advanced, one corrugation 10 at a time, one slide working in advance of the other and holding the previously formed corrugation while the second follows with a forming stroke. The metal is taken up from the uncorrugated end only. This 15 method limits the length of the sheets to the span between press housings and the rate of production to the permissible speed of the press. 60

The second method is semi-continuous and more rapid, but is also limited for sheet lengths by the housing span. The machine employed might be described as a pair of wide-faced gears, loosely meshed, and with a tooth-form like that of a finished corrugation. The gear-like corrugating rolls are rotated and a carefully timed device thrusts the sheets between them at such a point so that the first corrugation is formed in correct relation to the edge of the sheet. 75

35 Shrinkage, due to corrugating, is accommodated by the tail end of the sheet as in the first method. Though this method is more rapid, it is limited for sheet lengths. 80

Both of the foregoing methods have further disadvantages in that they set up excessive internal stresses and strains in the metal and have a very pronounced abrasive action on the surfaces of the sheets being corrugated. This is very objectionable, especially when sheets have been coated on the surface. 85

The prime object of my invention is to fold the corrugations into the sheet with my machine, thereby decreasing the internal stresses and strains due to forming to a 90

It is a further object of my invention to fold the sheets and form the crests and valleys of the corrugations continuously and successively in such a manner that there will be a minimum of abrasives action on the surface of the sheet. 65

Another object of my invention is to permit the sides of the sheet to advance equally towards a common center line while forming successive half corrugations. 70

A still further object is to overcome the limitations of other methods in the length or width of the sheet. In my machine, and because of the corrugating method employed by it, the practicable length of rolls limits only the sheet width, and there is practically no limit as to sheet length. 75

It is also my object to first form a central corrugation and thereafter fold as much of the sheet as is necessary to form the crests and valleys of successive corrugations alternately as the sheet progresses through the machine. That is, each succeeding roll folds over enough material for one-half of a corrugation. 80

Other objects, new and novel features will be more specifically described as the specification proceeds. 85

In the drawings:—

Fig. 1 is a top plan view of my machine for forming corrugations in sheet metals successively; 90

Fig. 2 is a side elevation of my machine showing how successive rolls are driven; 95

Fig. 3 is a diagrammatic illustration of the progressive steps of corrugation from start to finish over a width of a sheet; and 100

Fig. 4 is an enlarged view of one-half of a corrugation.

For purposes of illustration I have shown eleven stands of two-high rolls. The first set of rolls 1 and 1^a at the left end of my machine are rotatably mounted in the main side frames 1^c as are all the other corrugating rolls 2, 2^a, to 11, 11^a inclusive.

to be described. The rolls are gear-driven (to be described) and rotate in the proper direction to feed the sheet through the machine. These rolls 1 and 1^a are smooth on their surface and are used to start a sheet through the machine. When the sheet reaches a rotating set of rolls 2 and 2^a a central corrugation 2^c will be folded in the sheet by the convex ridge 2^b on the upper 5 roll 2 and a concave groove on the lower mating roll 2^a in which the convex ridge 2^b meshes. This aforementioned central corrugation is the only complete corrugation formed at one time and it is centrally located in order to definitely guide the sheet 10 as it continues through the machine.

On advancing between the next succeeding set of rolls 3 and 3^a two one-half corrugations 3^b (see Fig. 3) will be folded into the 15 sheet on each side of the central corrugation formed by the rolls 2 and 2^a. These half corrugations are formed by the concave grooves 3^c on the roll 3 and mating convex ridges on the roll 3^a. During the folding 20 operation the sides of the sheet will be equally drawn towards the center of the machine. Since the metal is only folded over a half corrugation at one time it is apparent that there will be a minimum amount of 25 abrasive action on the surface because no sliding action takes place.

Further advancement of the sheet through the machine passes it between the rotating rolls 4 and 4^a where two more half corrugations 4^b one on each side of the center, are formed. The additional convex ridges 4^c 30 are now on the upper roll 4 and the concave groove is on its lower mating roll 4^a. The sides of the sheet will again be drawn 35 equally towards the center as was the case while folding the sheet between the rolls 3 and 3^a.

For purpose of simplicity in the specification it is here stated that the convex ridges 4^b and concave grooves on mating rolls from 5, 5^a, to 11, 11^a, inclusive, will alternate in the same fashion as described for the rolls 3, 3^a, and 4, 4^a. In each case the one-half corrugations formed on a particular roll will 45 be identified by the letter *b*, and *c* will identify the corresponding convex ridge or concave groove for any particular set of rolls.

The direction of rotation of each of the rolls is indicated by arrows and since the 50 sheet must advance through the machine at a uniform rate of speed I have interconnected each set of rolls by gears 12 and 12^a which will necessarily rotate the rolls 55 at the same speed and in the proper direction. Between each stand of rolls I have placed the idler gears 13 which mesh with the gears 12 and drive these gears and the rolls. By referring to Fig. 2 it will be 60 seen how these gears will cause all the

rolls to rotate in the proper direction as indicated by the arrows.

A gear 14 which is similar to another idler gear is mounted in approximately the center of my machine on the shaft 15. This 70 gear is the source of power from the motor and drives all the rolls through the idler gears and the gears on the rolls. This gear is keyed on a shaft 15 which is journaled and rotates in the main frame 1^c in its bearings 75 15^a. Mounted on the opposite end of the shaft is a bull gear 16 which is driven by a train of gears 17 starting at the motor 18. The reason for locating my main drive approximately in the center is to decrease the 80 accumulative lost motion in the gears to a minimum and thereby insure uniform feeding of the sheet while folding the corrugations.

In my machine I feed flat sheets of any 85 length between the first set of rolls at the left which feed the sheet to the next set of rolls where a single complete corrugation is formed. On passing through each succeeding set of rolls two one-half corrugations are formed in a manner that is analogous to a pleating action. The sheet continues moving through the machine and the corrugations are formed successively until the entire sheet has passed through and it 90 will emerge from the right-hand end with neatly folded corrugations over the entire length of the sheet, all of the rolls assisting the feeding of the sheet during the folding 95 operation and holding the advanced portion 100 of the metal, while permitting the tail to fold.

Having thus described my invention, what I claim as new and desire to secure by Letters Patent, is:—

A machine for forming corrugations in sheet metal, which comprises a series of stands of rolls having circumferential ridges and matching grooves, said rolls arranged so that in the first stand a pair of opposed 110 folds is formed in the metal lengthwise and centrally thereof, and in the succeeding stands one fold is made at each side of the previously folded portions, and a drive for said rolls in the said stands, comprising a gear system between the several rolls of the several stands to drive all of them, and a main drive for said gear system located substantially centrally intermediate the said gear system, for the purpose described.
